UNITED STATES PATENT OFFICE.

OSCAR G. BRUSH, OF BAY CITY, MICHIGAN.

DESIGN FOR AN URN AND PEDESTAL THEREFOR.

No. 38,513.

Specification for Design.

Patented April 9, 1907.

Application filed March 4, 1907. Serial No. 360,623. Term of patent 7 years.

To all whom it may concern:

Be it known that I, OSCAR G. BRUSH, a citizen of the United States, residing at Bay City, county of Bay, and State of Michigan, have invented a new, original, and ornamental Design for an Urn and Pedestal Therefor, of which the following is a specification, reference being had to the accompanying drawing, forming part thereof.

The figure is a perspective view of the urn and pedestal, showing my new design.

I claim—

The ornamental design for urn and pedestal therefor, as shown.

OSCAR G. BRUSH.
